UNITED STATES PATENT OFFICE.

GEORGE F. WATT, OF CHICAGO, ILLINOIS.

CARD-INDEX FILE.

SPECIFICATION forming part of Letters Patent No. 700,391, dated May 20, 1902.

Application filed July 24, 1901. Serial No. 69,516. (No model.)

To all whom it may concern:

Be it known that I, GEORGE F. WATT, a citizen of the United States, residing in the city of Chicago, county of Cook, and State of Illinois, have invented a new and useful Improvement in Card-Index Files, of which the following is a specification.

My invention relates to card-index files for the keeping of records upon separate cards removably retained in specially-adapted receptacles; and the objects of my invention are, first, to provide simple and effective means for removably retaining the cards within the receptacle; second, to provide means for maintaining the angle-block in any desired position of adjustment; third, to provide an automatic locking device for insuring the retention of the cards in the tray or drawer when the latter is pushed home in its casing, and, fourth, to provide the other details more specifically hereinafter set forth. I attain these objects by the mechanism illustrated by the accompanying drawings, in which—

Figure 1 is a view of the complete device, taken in vertical longitudinal section. Fig. 2 is a plan view in section, taken on the line 2 2, Fig. 1. Fig. 3 is a transverse sectional view taken on the line 3 3, Fig. 1. Fig. 4 is a fragmentary view showing the construction of the lower portion of the angle-block in detail. Fig. 5 is a face view of a card, showing the configuration of the retaining-slot.

Similar letters refer to similar parts throughout the several views.

The outer casing comprises the top *a*, bottom *b*, side walls *c c*, and rear wall *d* for inclosing the tray or drawer wherein the cards are placed. Said drawer, which fits loosely within said casing, is open at the top and comprises the bottom *e*, sides *f f*, front wall *g*, and rear wall *h*. The rear surface of said front wall *g* is inclined, as shown, to facilitate the fingering of the cards arranged in the ordinary manner.

The rod *i* forms a guide for the angle-block *j* and has a bearing in the front and rear walls *g* and *d*, respectively, of the drawer. The said rod has the arms *k k* rigidly secured thereto preferably within and near the extremities of the drawer, and said arms carry at their extremities the retaining-rod *m*, which thus extends in a direction parallel to the

guide-rod *i* and may be swung in the arc of a circle about said rod *i* as a center. The purpose in thus swinging the rod will be evident if reference be had to Fig. 5, wherein the card *n* is shown to be provided with an inverted-L-shaped slot *o*, adapted to receive said retaining-rod and be retained thereby when said rod occupies a position in the horizontal portion of said slot, but be free to be withdrawn when said rod occupies a position in the vertical portion of said slot. The rod *m* is swung or rocked to the desired position by means of the controlling-lever *p*, which is pivotally connected to the upper extremity of the forward arm *k* and is pivotally supported intermediate of its extremities by means of the pin *q*. (Best shown in Figs. 1 and 3.)

In order to impart a neat appearance to the device, and also for the purpose of removing the lever *p* and its connections from possible interference with the cards, it is desirable to chamber the front wall *g*, so that the arm *k*, lever *p*, and forward portion of the retaining-rod *m* shall be inclosed within said front wall in the manner shown. For convenience of manufacture it is preferable to construct said front wall *g* in two parts. The parts are so proportioned that the upper extremity of the lever *p* projects above the rear portion of the front wall, and is thereby accessible to the operator. For the purpose of attaining symmetry and avoiding the necessity of unduly slotting the lever *p* at the pin *q*, said lever and connected parts are so arranged that when said lever is at one extremity of its throw said rod lies at the closed extremity of the horizontal portion of the slot *o*, and when said lever is at the other extremity of its throw said rod lies in the vertical portion of said slot.

In order to insure the retention of the cards in the drawer when the latter is in place within the casing, the block *r*, the forward face whereof extends obliquely crosswise of the drawer, is secured to the rear wall *d* of the casing in line with the retaining-rod *m*. The said rod *m* projects through the suitably-apertured rear wall *h* of the drawer in such a manner that when said drawer is pushed home within the casing the projecting extremity of said rod will engage said block and, on account of the obliquity of the face of the lat-

ter, will be thrown over to such a position as to lock the cards in place.

When a card is to be withdrawn or inserted, the operator throws the lever *p* to its extreme position, so that the rod *m* lies within the vertical portion of the L-shaped slots *o* of the cards, thus permitting the cards to be moved vertically into or from the drawer. The subsequent locking of the cards is attained by throwing the rod *m* over into the horizontal portion of the slots *o*, and this may be accomplished either by the operator's throwing the lever *p* or by simply pushing the drawer completely into the casing. In the latter instance the rearwardly-projecting extremity of the rod *m* will be automatically thrown by means of the locking-block *r*.

The angle-block *j* above mentioned has attached upon the bottom thereof the sleeves *s* and *t* for guiding said block upon the rod *i*. The sleeve *s* is rigidly secured at the forward portion of the block, while the sleeve *t* is hinged to the rear portion thereof, as best shown in Fig. 4. The rear extremity of the sleeve *t* is free to swing vertically through a small arc, for the reason that the internal diameter of said sleeve is somewhat greater than the diameter of the rod *i*. The spring *u* is secured to the bottom of the block *j* and tends to depress the rear extremity of said sleeve *t* and cause the same to bind or cramp the rod *i*, thus preventing the travel of said block within the drawer. The sleeve is released by means of the lever *v*, which is operated by the button *w* and connected to the rear extremity of said sleeve *t* by means of the tension rod or wire *x*. Said lever *v* is pivoted between its extremities, the button *w* and rod *x* being connected on opposite sides of the pivot, and the parts are so arranged that the depression of said button causes the raising of the rear extremity of the sleeve *t* against the force of the spring *u*. The block *j* is suitably chambered to receive the rod *m* and permit the necessary lateral motion thereof. In the adjusting of the angle-block for the accommodation of the number of cards temporarily in use the button is pressed by the operator, which causes the sleeve *t* to release the guide-rod *i* and at the same time permits the operator to move the block backward or forward in the drawer. As soon as the hand of the operator is removed from the button the spring *u* forces the sleeve *t* upon the guide-rod and holds the said angle-block *j* stationary.

What I claim as new, and desire to secure by Letters Patent, is—

1. A card-index file having an adjustable angle-block, cards provided with slots extending both vertically and horizontally; a pair of rods, whereof one is revolvably supported in the card-receptacle and forms a guide for the angle-block, and the other of said rods is connected to said guide-rod above the same for entering the slots within the cards, and means

for throwing said retaining-rod laterally about the guide-rod as an axis.

2. A card-index file comprising a casing, a drawer sliding therein, cards provided with slots extending both vertically and horizontally; a retaining-rod mounted in said drawer and capable of lateral motion for retaining or releasing the cards, said rod having a part projecting beyond the inner extremity of said drawer; and a locking-block secured to said casing, said block having an oblique face for engaging and laterally shifting said retaining-rod to retain said cards.

3. In a card-index file, the combination with the casing and drawer sliding therein, of an adjustable angle-block, cards provided with slots having both horizontal and vertical portions, a guide-rod for said angle-block journaled in the drawer, arms extending from said guide-rod, a retaining-rod carried by said arms and capable of lateral motion for engaging and releasing said cards, said retaining-rod projecting beyond the inner extremity of said drawer, and a locking-block having an oblique face adapted to engage said retaining-rod, whereby said rod is laterally shifted when said drawer is pushed home.

4. In a card-index file, the combination with the card-receptacle of an angle-block, a rod for guiding the same, a spring secured thereto, a sleeve hinged to said block and loosely encircling said guide-rod, said spring forcing said sleeve against said rod for cramping the latter to thereby prevent the travel of said angle-block, a lever mounted in said angle-block, said lever being connected to said sleeve for raising the same free from said rod, and means for operating said lever.

5. In a card-index file the combination with the card-receptacle of an angle-block, a rod for guiding the same, a spring secured to said block, a sleeve hinged to said block and loosely encircling said guide-rod, said spring forcing said sleeve against said rod for cramping the latter to thereby prevent the travel of said angle-block, a lever mounted in said block, and pivoted between its ends, a rod connecting said lever to said sleeve for raising the latter free from said rod and a button secured to said lever, said button and sleeve-operating rod being on opposite sides of the lever-pivot, whereby the pressing of said button releases said sleeve.

6. In a card-index file, the combination of a drawer for containing the cards, a casing for inclosing said drawer, cards provided with slots having portions extending horizontally and vertically, an adjustable angle-block, a guide-rod for said angle-block journaled in the ends of the drawer, arms extending from said guide-rod, a retaining-rod carried by said arms and capable of lateral motion for engaging and releasing said cards, said retaining-rod projecting beyond the inner extremity of said drawer, a locking-block secured to said casing, and having an oblique face for shift-

ing said guide-rod, a sleeve hinged to said angle-block and loosely encircling said guide-rod, a spring secured to said angle-block and operating upon said sleeve to force the latter against said rod, a lever pivotally mounted in said angle-block, a hand-operated button attached to said lever, and connections between

5 said lever and said sleeve whereby the latter may be released from the guide-rod.
